UNITED STATES PATENT OFFICE

EDMUND MORRIS, OF GRAND RAPIDS, MICHIGAN, ASSIGNOR TO GRAND RAPIDS STORE EQUIPMENT CORPORATION, OF GRAND RAPIDS, MICHIGAN, A CORPORATION OF MICHIGAN

ADJUSTABLE PARTITION SUPPORT

Application filed June 11, 1928. Serial No. 284,446.

This invention relates to an adjustable partition support which is particularly useful in connection with supporting vertical glass partitions across the tops of counters, tables or the like used in stores to carry and display articles of merchandise. It is an object and purpose of the present invention to provide a simple and effective construction whereby the partitions may be securely held in vertical position but can be adjusted to a large number of different positions over the top of the counter or table very quickly and easily.

An understanding of the invention may be had from the following description taken in connection with the accompanying drawing, in which,

Fig. 1 is a fragmentary perspective view illustrating an embodiment of my invention for adjustably mounting and holding vertical partitions above and across a counter or table top.

Fig. 2 is a fragmentary vertical section taken through the auxiliary top shown in Fig. 1 and illustrating the immediate partition holder member in elevation.

Fig. 3 is a fragmentary perspective view showing the bar on which the immediate partition holding members is adjustably mounted together with said member, and

Fig. 4 is a fragmentary perspective view showing a different form of bar on which to mount the partition holders.

Like reference characters refer to like parts in the different figures of the drawing.

The counter or table top 1 at its opposite side edges has vertical border members 2 secured thereto and at its opposite end edges similar vertical border members 3, these border members being secured in any suitable and desired manner.

In the illustration of the invention as shown in Fig. 1, an auxiliary top is placed over the main top 1 and located above its upper side within the surrounding border members. Said auxiliary member includes a plurality of cleats or sills 4 spaced apart from each other and extending across the top 1. To these cleats panels 5 are attached adjacent the ends of the cleats while a wider panel 6 is at-

tached to said cleats over their intermediate portions being spaced at its edges a distance from the adjacent edges of the side panels 5. In practice the panels 5 and 6 are made of multiple ply veneer though it is to be understood that the particular materials used in making the panels is no feature of the present invention.

In the elongated spaces between the adjacent edges of the panels 5 and 6 at each side of the auxiliary top, a sheet metal supporting bar is located. In practice the bar consists of an under flange 7 which at one edge is turned upwardly to make a web 8 and then bent back parallel to the under flange 7 to provide an upper narrower flange 9. The width of the flange 7 is equal to the distance between the adjacent edges of the panels 5 and 6. Suitable openings 10 are made in the lower flange 7 at points over the cleats 4 in order that fastening devices, such as screws, can be passed through the openings to secure the supporting bars to the cleat 4. The upper flange 9 is located with its upper side flush or in the same horizontal plane with the upper sides of the panels 5 and 6. Vertically alined openings 11 spaced short distances apart are made through the flanges 7 and 9 as fully shown in Fig. 3.

The immediate partition holders comprise U-shaped spring clips each having a horizontal bottom 12 from which vertical fingers extend upwardly substantially parallel to each other but normally converging slightly toward their upper ends, but directly at the upper ends being bent outwardly as shown in Fig. 3. A pin 14 is connected with and extends downwardly from the bottom 12 of each partition holding member. The pins 14 are of a size to be freely received in any two vertically alined openings 11 in the flanges 7 and 9, and can be shifted from one position to another along the lengths of the supporting bars therefor.

It is evident that with two of the partition holding members suitably located at opposite sides of the auxiliary top the holding members for a partition 15, which preferably is of glass, may be turned so as to readily receive the partition which is placed down-

wardly between fingers 13. The partition 15 is of a length to be received between the opposite side border members 2 and be at its ends in substantially close engagement with the inner sides of the members 2. By adjusting the partition holding members to different positions, the widths of the compartments made between said partitions or between the same and the end border members 3 may be varied and changed as is evident.

Instead of making the bar of the sheet metal form as shown in Figs. 1, 2 and 3, it may be a solid bar 16 of metal, as shown in Fig. 4, rectangular in cross section and having the same thickness as the panels 5 and 6 and with openings 11^a to receive the pins 14; while the openings 10^a will be countersunk at their upper ends in order that the screws attaching the bar to the cleat 4 may have the upper sides of their heads flush with the upper side of the bar.

While this construction has been illustrated as applicable to an auxiliary top it is evident that it may be used quite as effectively by placing the supporting bars for the immediate partition holding members in grooves cut in the upper side of the main top 1.

The invention permits the quick and easy adjustment of vertical partitions as described and at the same time serves to hold said partitions securely in any position in which placed. The invention may be varied in many particulars from the specific disclosure made and is, therefore, to be considered comprehensive of all forms of structure coming within the scope of the appended claims defining the invention.

I claim:

1. In combination with a horizontal top member, a bar located adjacent a side edge of said member, said bar having a plurality of spaced apart vertical openings therein and having its upper side substantially flush with the upper side of the top member, a U-shaped clip located above the bar comprising, a base and upwardly extending spaced apart fingers, and a pin connected to and extending downwardly from said base, said pin being removable from and received within any of said vertical openings in said bar.

2. In combination with a horizontal top member, a horizontal bar located adjacent each side edge of the top member, said bar being of sheet metal and comprising a lower horizontal flange, a vertical web at one side edge of the lower flange and an upper horizontal flange located above and parallel to the lower flange, said upper flange having a plurality of spaced apart openings in its length, a partition holding and receiving means located above the upper flange of the bar and extending upwardly therefrom, and a pin connected to the lower portion of said partition holding means adapted to be re-

ceived in or removed from any of said openings in said upper flange.

3. A construction containing the elements in combination defined in claim 2, said lower flange of the bar having a plurality of openings therein in vertical alinement with the openings in the upper flange, said pin when applied to the bar extending through the opening in the upper flange and into an opening in the lower flange.

4. In a device of the character described, a bar having a series of openings therein, a U-shaped clip located above the bar comprising, a base and upwardly extending spaced apart fingers, and a pin extending from said base, said pin being removable from and received within any of said vertical openings in said bar.

In testimony whereof I affix my signature.

EDMUND MORRIS.
